UNITED STATES PATENT OFFICE.

BENJAMIN F. CORWIN, OF BROOKLYN, NEW YORK.

COMBINED DISINFECTOR AND LAMP.

No. 924,433.

Specification of Letters Patent.

Patented June 8, 1909.

Application filed January 7, 1909. Serial No. 471,188.

To all whom it may concern:

Be it known that I, BENJAMIN F. CORWIN, a citizen of the United States, residing at Brooklyn, in the county of Kings and State 5 of New York, have invented new and useful Improvements in Combined Disinfectors and Lamps, of which the following is a specification.

This invention relates to a combined dis- 10 infector and lamp.

The invention is useful for physicians or any person desiring a convenient and portable thermometer case or a convenient and easily portable alcohol lamp or a combina- 15 tion of the two.

This invention is set forth in the following specification and claims and illustrated in the annexed drawing in which:

Figure 1 shows an alcohol lamp and disinfecting thermometer case embodying this invention and being collapsed or brought into compact form to be carried in the pocket. Fig. 2 is a vertical central section of Fig. 1. Fig. 3 shows the device converted into a 25 lamp.

In this drawing is shown a receptacle *a* of suitable material or metal. In this receptacle is formed a constriction by means of a diaphragm *c*. A cover *b* can be applied to 30 close the receptacle air tight or so as to prevent escape of alcohol or contents from the receptacle.

In the diaphragm or partition *c* the opening *d* is adapted to receive or suspend a thermometer or instrument which can be disinfected by its contact or insertion into the alcohol. The opening *d* may have a lining *e* of metal or suitable material and project somewhat above the level of the diaphragm and 40 can be flared as indicated. The thermometer can be fitted with a rubber band to prevent the escape of alcohol. The cap or cover *b* has its upper part formed in shape of a nipple portion and when the thermometer 45 is withdrawn the upper part of the receptacle cover *b* can be used as a plug or inserted into and made to close the opening *d*.

Opposite the diaphragm at the lower end of the case *a* is an opening *f* into which is inserted a tube *g*. This tube opens upwardly

into the receptacle so that alcohol in the tube will enter and charge the tube *g*. The upwardly opening end is indicated at *k*. The downwardly opening end of tube *g* is indicated at *j* and in its lower end this tube *g* has 55 an absorbent *i* saturated by the alcohol entering the tube. The tube *g* is fitted tightly into an opening in the lower part of the receptacle *a* and the lower opening *j* has a cover or screw top *h* applied over the same to 60 prevent escape of alcohol from the receptacle through the tube when the receptacle is in upright position.

When the device is to be used as a lamp the receptacle is inverted and the cap *h* removed and the alcohol or combustible which has been absorbed by the asbestos or material *i* can be ignited producing a flame rising through opening *j*. When no longer to be used as a lamp the cap *h* can be screwed 65 back in place, the receptacle turned right side up to receive an instrument as before and the cap or cover *b* screwed back in place for the device to serve as a disinfecting receptacle.

The burner tube *g* is partly contained in the receptacle and is made to telescope or slide therein to be moved outward when serving as a burner and slid inward when not in use so that the instrument can be brought to 80 compact form. The burner tube *g* can have a rubber band *m* applied thereabout to prevent leakage through opening *f*.

What I claim is:

1. A combined disinfecter and lamp comprising a receptacle with a constriction adapted to support an instrument to be disinfected said constriction being located at the upper part of the receptacle, a cover for the upper part of the receptacle, a burner tube slidably mounted in the opposite part of the receptacle, and a cap made to form a closing nipple for the burner tube, the cover for the upper part of the receptacle having a portion made to fit the constriction to act as 95 a stopper for the same.

2. A combined disinfecter and lamp comprising a receptacle with a constriction adapted to support an instrument, said constriction being located at one part of the 100

2 11/14/1911
receptacle, a burner tube in the opposite part of the receptacle opening upwardly into said receptacle and having absorbent at its lower portion to receive combustible from the receptacle, and a removable cap to close the burner tube when not in use.

In testimony whereof I have hereunto set

my hand in the presence of two subscribing witnesses.

BENJAMIN F. CORWIN.
